UNITED STATES PATENT OFFICE.

WASHINGTON OTTO MAC KEY, OF SODERTALJE, SWEDEN.

MUD PROTECTOR FOR AUTOMOBILES AND THE LIKE.

Application filed September 19, 1925, Serial No. 57,411, and in Sweden June 6, 1923.

This invention has for its object a mud-protector for automobiles and similar vehicles and comprising a ring-shaped plate-band to be fixed to the wheel-rim on one or both sides and proportioned to the same and having a ring-shaped dash-board of flexible material fixed to it, the said plate-band extending radially or approximately radially outwards along the wheel-rim nearly to the middle of same.

The invention is described below conformably to a form of same shown in the annexed drawing where

Figure 1 is a side-view of an automobile-wheel provided with the said mud-protector.

Figure 2 is a cross-section of the said wheel, and

Figure 3 shows a modified detail.

The mud-protector in question is to be applied to both sides of the wheel, and 4 and 5 mark the plate-bands and 1 and 2 the ring-shaped dash-boards which may be made out of india rubber, leather or another flexible material. The two plate-bands 4, 5 are shaped by the inside of the felloe and adapted to rest against it. Each of the dash-boards 1, 2 is fixed along its inner circumference to a plate-band in any suitable manner as for instance by rivets 6 and a narrow plate-ring 7 and 8 respectively mounted on the inside of the bands, the inner ends of the rivets having been upset against the said plate-rings. The dash-boards may also be fixed to the plate-bands in a detachable manner as for instance by means of keys for being interchanged, if wanted. Each plate-band may extend at least to the middle of the wheel-rim, viewed in cross-section, in order to give to the dash-board a sufficient support against being bent outwards, and also for imparting to the same a correspondingly curved shape which besides gives to the mud-protector a more favourable look. The breadth of the dash-board is adapted to the wheel-rims of the vehicle in such a manner as to allow the dash-boards to come as near to the ground as possible for filling their task in an effective manner. All rings may be composed of sections.

By the shown arrangement of the mud-protector one gains the advantage of the dash-boards being able to bend freely inwards towards the wheel-rim to avoid unevennesses of the ground and also to be supported against being bent outwards.

Different means may be used for fixing the mud-protector to the wheel-rim. Below three different means are mentioned adapted to a carriage-wheel, a wheel with steel spokes 60 and a disc wheel respectively.

A means for fixing the mud-protector to a carriage-wheel is shown in Figure 1. The two plate-bands 4, 5 are pressed to the felloe by locking members which are jammed between the felloe and the hub. The said members comprise a clamp 9 of sheet-metal or the like embracing the plate-bands and provided with a tube 10 directed inwards, a bolt 11 being slidably mounted in the said 70 tube. The said bolt ends in a wedge 12 of india rubber or another suitable material which extends between two spokes. A strong spiral spring 13 provided between the bolt 11 and the bottom of the tube produces the 75 pressing action necessary for retaining the plate-bands. When the said means has been mounted in its place the tube 10 and the bolt 11 may be locked together by means of a screw 16. In order that the wedge 12 may 80 be firmly fixed in its place it may be provided with a stud or the like formed out of the bolt or fixed to it and engaging either a corresponding depression made in the hub 85 or the space between the spokes.

The means for fixing the mud-protector to a wheel with steel spokes shown in Figure 3 consists of hooks 14 fixed to each of the plate-bands 4, 5 with equal interspaces, the said figure showing one hook in each ring. 90 As shown in the drawing the respective hook is provided on one plate-band opposite a hook on the other one, a spiral spring 15 being mounted between both hooks, the ends of said spring forming each a swivel with 95 loop, or also a loop only for fixing the spring. Evidently, the plate-bands 4, 5 are pressed to the wheel-rim by the said means.

In disc-wheels or wheels with removable feloes the mud-protector is suitably fixed 100 by means of the traversing screws uniting the discs or fastening the felloe, the plate-bands being provided with holes suitable for the said purpose. It is evident that other fastening means may also be used.

Having now described my invention, what I claim as new and desire to secure by Letters Patent is:

1. A mud protector for automobiles and like vehicles, comprising a ring shaped plate 110 band adapted to fit over the inner surface of the wheel rim, means for securing said

plate band to said rim, comprising a plurality of clamps situated at a suitable distance from one another between the spokes of the wheel and adapted to embrace the plate band, said clamp having tube members, extending inwardly toward the hub of the wheel, bolts slidably mounted in said tube members, the outer ends of said bolts terminating in wedges adapted to extend between two spokes at the hub, and means for forcing said bolts against said spokes, and a ring shaped dash board of flexible material, secured to said plate band in such a manner as to allow the same to bend freely inwardly toward the wheel rim, but to support the same against outward bending.

2. A mud protector for automobiles and similar vehicles, comprising a ring shaped plate band adapted to be secured to the wheel rim and proportioned to the same, having a ring shaped dash board of flexible material secured to either side thereof and extending beyond the same, said plate band extending substantially radially outward along the

wheel rim nearly to the middle of the same, 25 said dash board extending inwardly by nearly the half of its breadth along the inside of the plate band, and being secured thereto at its inner circumference only, whereby said dash board is permitted to bend freely 30 inwardly toward the wheel rim to avoid unevenness of the ground, yet is supported against outward bending, a plurality of clamps embracing the plate band, located at a suitable distance from one another between the spokes, and having tube members 35 extending inwardly therefrom, toward the hub of the wheel, bolts slidably mounted in said tube members and having ends which terminate in wedges of flexible material 40 adapted to abut the intersection of two spokes, springs in said tube members for forcing said bolts against said spokes, and set screws for locking said bolts in engaging position. 45

In witness whereof, I have hereunto signed my name.

WASHINGTON OTTO MAC KEY.
